KASSIE SAWDER PARRISH, OF PARISH, FLORIDA

ORCHARD HEATER

Application filed May 2, 1929. Serial No. 359,942.

This invention relates to orchard heaters and has for its object the production of a simple, cheap, readily constructed, installed, and operated heater.

Orchard heating requires a large number of heaters to be effective and hence the first cost of the same is an exceedingly important factor. Similarly, effective heating of an orchard requires a form of heater that will operate on crude oil, still residues and other low cost fuels.

Heaters previously designed for this purpose have been complicated in construction and consequently expensive to manufacture. Elaborate vaporizing means have been suggested so designed that when the oil contacts with the air it is in vapor form. In other cases burners of complex form have been proposed, such as annular troughs with means for introducing air around said trough and also through its center opening. Arrangements have also been proposed so that in operation the burning oil would heat the container for liquid oil which is obviously undesirable.

I have found that these complicated forms of construction are wholly unnecessary and that very satisfactory results may be obtained by using as the body of the burner a plain tube having within it liquid-filming means to allow the oil to spread out and burn. Such oil-filming means are designed so that while they retain the greater part of the oil fed thereto they permit the passage of air for the combustion of the oil. Air may enter the tube through apertures in the side thereof or through the lower end or by both methods.

Where air is to be introduced through the lower end of the burner tube some means are required for holding the tube off the ground. Conveniently this is accomplished by attaching to the burner tube a stake or stakes which may be thrust into the ground and thus hold said burner tube upright with its lower margin above the ground level.

The crude oil or the like is burnt on a suitable grate arranged in the burner tube desirably intermediate its ends to avoid flames passing around the lower margin of

the burner tube. Various forms of grate may be used, the most desirable being those comprising finely pervious material adapted to spread the oil out into thin films and at the same time allow ready access of air to the films so produced. One of the cheapest and simplest forms of such grate consists of one or more gauze grids supported in the burner tube intermediate its ends, onto which grids the liquid fuel is allowed to drop. Most of the oil is retained on these grids and is burnt thereon while the balance of the oil drops to the ground and burns there.

Two forms of my orchard heater are shown, by way of example of suitable constructions in the accompanying drawings.

In the drawings:

Fig. 1 is a side elevation of the heater with the burner in section,

Fig. 2 is a side elevation of a modified form of construction,

Fig. 3 is a section on the line III—III of Fig. 1.

In both forms of construction the burner consists of a tube 1, conveniently formed of galvanized iron or the like, open at both ends. At its lower end a pair of bars or strips 2 are riveted thereto to serve as legs or supports for the burner. These bars 2 are pointed at the bottom so that they may be thrust readily into the ground 3 as shown.

In the lower part of the tube are arranged one or more gauze grids 4 onto which the crude oil or other fuel is dropped. The mesh of this gauze is sufficiently fine to retain at least the major part of the oil dropped thereon, so that these grids serve as the grate on which the liquid fuel is burned. These grids may be supported in various ways, one of the most convenient being by means of two pins 5 at right angles, the ends of these pins passing through holes in the tube 1, while the middle portions are wired together where they cross each other. When two or more grids are used they may be supported separately or may be stacked one on top of the other. This latter method is especially convenient and suitable when the grids are formed, as shown, with an upwardly extend-

ing flange which serves to carry the grid next thereabove.

While the bottom of the tube 1 is above the ground so that air may pass under its lower edge, additional air may be supplied for combustion by providing holes 6 in the tube below the grids. The close weave of the gauze grids required to retain the major part of the oil has the effect of retarding upward flow of air through the tube and hence, while not always necessary, it is usually advantageous to provide additional air-holes 7 above the grids to aid in the complete combustion of the fuel.

15 The two forms of construction shown are similar except as regards the method of supporting the fuel container. In Fig. 1 the fuel container 8 is mounted on a stand or pedestal 12, not connected in any way with the burner 1. From the lower part of the container 8 a pipe 9 extends laterally and then downwardly into the top of the burner tube. A control valve 10 regulates the amount of oil discharged onto the grid.

25 In the form of construction shown in Fig. 2 the fuel container 8 is supported by a bracket 11, riveted or otherwise secured to the side of the burner tube.

It will be noted that in both forms of construction the fuel container is to one side of the burner tube. This, while not essential, is advantageous as it avoids the direct heat of the burner tube playing on the fuel container.

What is claimed is:

35 1. An orchard heater comprising a metal tube open at both ends, a foot secured to the lower end of said tube extending a considerable distance below said tube to allow such foot to be inserted in the ground to a depth sufficient to give lateral support to the heater without bringing the bottom of the tube into contact with the ground, liquid fuel filming means in said tube intermediate its ends, a container for liquid fuel and means for discharging fuel from said container onto said fuel filming means, the space below said filming means being sufficiently unobstructed to allow liquid fuel draining off said filming means to drop to the ground and burn there.

45 2. An orchard heater comprising a metal tube open at both ends, means for supporting the tube with its lower end above the ground, a gauze grid in said tube, supporting pins for said grid passing through holes in the tube, a container for liquid fuel and means for discharging fuel from said container onto said grid, the space below said gauze grid being sufficiently unobstructed to allow liquid fuel draining off said grid to drop to the ground and burn there.

55 3. An orchard heater comprising a metal tube open at both ends, a container for liquid fuel, a support therefor secured to the upper end of the tube, a plurality of pointed feet secured to the lower end of said tube extend-

ing a considerable distance below said tube to allow such feet to be inserted into the ground to a depth sufficient to give lateral support to the heater without bringing the bottom of the tube into contact with the ground, a gauze grid in said tube intermediate its ends and means for discharging fuel from said container onto said grid, the space below said gauze grid being sufficiently unobstructed to allow liquid fuel draining off said grid to drop to the ground and burn there.

4. An orchard heater comprising a metal tube open at both ends, a container for liquid fuel above the upper end of said tube and at one side of the same, a support for said container secured to the upper end of the tube, supporting means attached to said tube adapted to be thrust into the ground to hold said tube upright, fuel filming means in said tube intermediate its ends and means for discharging fuel from said container onto said fuel filming means through the flames from the fuel burning on said filming means to heat such fuel before it reaches said filming means.

5. An orchard heater comprising the combination, with a hollow cylindrical body portion open at both ends, and supporting means attached thereto adapted to be thrust into the ground to hold said body portion upright, of grid means comprising finely pervious material arranged within said body portion adapted to receive and film out liquid fuel while permitting distributed access of air thereto, and means for feeding liquid fuel upon said grid means.

6. An orchard heater comprising a tube open at both ends, means for supporting said tube in an upright position with its lower end off the ground, liquid fuel filming means in said tube and means for feeding liquid fuel at an adjustable rate upon said filming means.

7. An orchard heater comprising a plain straight tube, liquid filming means in said tube, a reservoir for liquid fuel at one side of said tube, and means for feeding liquid fuel at an adjustable rate from said reservoir upon said filming means, said tube having openings below said filming means for the entry of air and above said filming means for the discharge of products of combustion.

In testimony whereof I hereunto affix my signature.
